UNITED STATES PATENT OFFICE

JOSEPH LOUIS SCRIVENER, OF MCLEAN, VIRGINIA

LATCH BOLT

Application filed June 10, 1929. Serial No. 369,717.

This invention relates to improvements in latches, and more particularly concerns the construction and arrangement of the parts of such devices whereby the latch may be assembled upon a support by simple mechanical operations without involving major cutting or mortising.

One of the features of the present invention, therefore, is the provision of a cheaply made and simply installed latch which may be attached to a door, for example, by boring two holes through the door structure, and providing a simple recess for the latch bolt plate.

15 Another feature of this invention is the provision of means whereby the latch bolt may be blocked against movement by operation of a blocking plunger readily accessible to a person at one side of the door.

20 A further feature of the invention is the provision of this blocking plunger in the form of a member sliding in a hollow knob shaft and engaging with the latch bolt proper to block it against retractive movement, whereby the latch bolt assembly and the knob assembly are both fixed rigidly against movement when the plunger is in the blocking position.

25 Still another feature of the invention is the provision of a knob shaft which is rigid with the knobs and is prevented from axial movement of displacement by its operative engagement with the latch bolt assembly.

30 Further objects and features of this invention will appear in the course of the following specification and claims.

In the drawings is set forth an illustrative form of practicing the invention, in which:

35 Figure 1 is a horizontal sectional view substantially on line 1—1 of Fig. 2, showing the latch in position on a door.

40 Fig. 2 is a similar vertical section substantially on line 2—2 of Fig. 1.

45 Fig. 3 is a plan view, partially broken away, of the knob shaft and its associated parts.

Fig. 4 is a section thereof substantially on line 4—4 of Fig. 3.

50 Fig. 5 is a plan view of the plunger removed from the hollow knob shaft.

Figs. 6 and 7 are respective end views of this plunger.

Fig. 8 is a plan view of the latch bolt removed from the latch bolt tube.

Fig. 9 is a corresponding side elevation of 55 the latch bolt.

Fig. 10 is a sectional view on line 10—10 of Fig. 9.

Fig. 11 is an end elevation of the spring stop plate for the latch bolt. 60

Fig. 12 is a side elevation of the latch bolt tube.

Fig. 13 is an inner end elevation of the same.

Fig. 14 is a fragmentary sectional view 65 corresponding to a part of Fig. 2, with the knob shaft rotated through an angle of 90°.

Fig. 15 is a perspective view of the securing slider for the spring stop plate.

The latch according to the present invention comprises two assemblies which may each be located substantially in a cylindrical hole bored in the door, these holes being located at right angles to one another and extending respectively from the edge of the door for the latch bolt assembly and between the faces of the door for the knob shaft assembly. The latch bolt assembly is first located in its hole, and then the knob shaft assembly is brought into position and engagement with the latch bolt assembly, and thereafter the parts are held in their relative positions so that they reciprocally sustain one another against axial movement except as controlled by the knobs. The latch bolt assembly includes a bridge 80 member operable by a cam on the knob shaft assembly for the retraction of the latch bolt: while the knob shaft assembly further includes an axially movable plunger adapted to be moved past the bridge wherewith the bridge is located between the cam and the plunger so that both the knob shaft and the latch bolt are held against movement in such blocking position of the plunger.

Referring to the drawings, the door D is 95 provided with a cylindrical bore hole E extending from its edge and of a sufficient diameter to receive the latch bolt tube 10: while a cylindrical bore hole F extends from face to face of the door and intersects the bore hole 110

E at substantially a right angle, and permits the reception of the knob shaft. It is preferred to provide the latch bolt tube 10 with an edge flange or plate 11 (Fig. 2) projecting upwardly and downwardly, and receivable in a shallow mortise 12 provided in the edge of the door. From Fig. 13 it will be seen that the upper and lower ends of this flange 11 are rounded, and the flange itself is of the same diameter as the tube 10 proper, so that the workman may form the mortise 12 by simply drilling with a bit two shallow holes in line with the bore hole E, and cutting away the small remaining portions of wood with a penknife, whereby the operation of boring the door for the insertion of the latch is reduced to the drilling of two holes at right angles to one another, and the formation of a shallow mortise at the edge of the door by two further drilling operations and a brief cutting with a knife or chisel.

Referring to Figs. 2, 8, 9, 12 and 13, it will be seen that the exposed face of the flange 11 is provided with a rectangular opening 11a for the reception of the beveled striking end 13 of the latch bolt proper. The interior of the tube 10 is formed with the recessed guide portions 14 to receive the sliding members 15 of the latch bolt and to form a primary guide for them with respect to rotation about the axis of the latch bolt tube, being assisted in this by the engagement of the latch bolt end 13 with the walls of the opening 11a. The latch bolt tube 10 has a pair of alined transverse openings 16 therethrough.

The latch bolt proper has the sliding members 15 rigidly connected to the beveled end 13 and extending in parallelism inwardly and being connected at the extreme inner ends by a latch bolt bridge 17. These sliding members 15 have two pairs of alined slots 18 and 19 therein, of which the slot 19 has its inner ends terminating substantially flush with the outward face of the bridge 17. The pair of slots 18 receive the ends 20 of the spring stop plate 21. The latch spring 22 is received over the inwardly projecting lug 23 on the inner surface of the beveled end 13, and is secured by a clamping screw 24 to the relatively outwardly directed surface of the spring stop plate 21.

The knob shaft is assembled rigidly with the knobs K, Ka. The shaft proper is illustrated as being formed of three parts, comprising the outdoor end section 30, the indoor end section 31 and a central section 32 having a middle portion of the same diameter as the ends 30 and 31, but itself having reduced ends 33 fitting within the end portions 30, 31 and fixedly secured thereto as by screws 34. The knobs K, Ka may be of any desired pattern, and identical in form, being provided with the sleeves 35 which fit over the outer ends of the shaft portions 30, 31 and may be provided interiorly with the

pins 36 which are received in notches 37 formed in the respective ends of the shaft whereby the knobs are prevented from rotation upon the shaft in case the knob securing screws 38 become loose or be withdrawn.

The shaft end 31 at the interior of the door is provided with alined opposite slots 39 which have the small depressions 40, 40a formed therein near the opposite ends (Figs. 1 and 3), these depressions narrowing toward the exterior of the shaft portion 31 so that the respective slot has straight external edges from end to end.

Received within the shaft end 31 is a plunger member 41 adapted to slide axially in this tube and having a notch 42 cut from the end adjacent the inner knob to receive the screw 38 when the plunger is slid back and forth. This plunger likewise has a tongue 43 guided in the interior of the hollow central portion 32 of the shaft and in part by the securing screw 34. The plunger is provided with a transverse hole 44 having extending grooves 45 opposite one another and in a plane at a right angle to the axis of the plunger.

Spring cups 50 are adapted to slide in the hole 44 and in the respective slots 39, being hollow to receive the blocking spring 51 located between them and tending at all times to force them relatively outwardly. The cups are likewise each provided with the ears 52 which may slide in the extending grooves 45 of the plunger 41, or be received in the notches 40, 40a whereby in the latter position to lock the plunger against axial movement in one direction or the other.

The central member 32 of the knob shaft is provided at the point opposite the bridge 17 of the latch bolt with a cam member 60 which extends beyond the cylindrical surface of the knob shaft portions 30, 31, 32: this member 32 being cut away at 62 opposite this cam 60 by an axial distance corresponding to the thickness of the bridge member 17 (Fig. 8), so that the flat bridge member may enter this cut away portion 62 (Fig. 2) when the beveled end 13 of the latch bolt moves to its projected position.

The initial assembly of the parts of the latch bolt may be accomplished as follows: The latch bolt spring 22 is fastened to the spring stop plate 21 by the screw 24, and by rocking this plate with respect to the axis of the latch bolt slide members 15, the ends 20 of the stop plate are brought into their intended position in the slots 18, and the other end of the spring 22 engaged over the lug 23. This sub-assembly is then simply slid into the latch bolt tube 10, the slider members 15 being guided in the recessed portions 14 of the tube 10. An instrument is then introduced through the inner end of the tube 10 to depress the spring stop plate 21 slightly whereby to expose freely one of the openings

16, through which is now slid the latch bolt assembling pin 65 (Fig. 15) which has a central portion of diameter corresponding to the inner diameter of the tube 10, and projecting ends of diameter not greater than the external diameter of the tube 10. The central portion is directed away from the edge of the door (Fig. 1), and the pin is forced in, possibly with a pressure against its inwardly moving end through the inner end of the tube 10, until this inner end is brought into the opposite opening 16, whereupon the central portion of this pin 65 is forced by the spring 22 into the securing position shown in Fig. 1. The latch bolt assembly is now complete.

The initial knob shaft assembly may be accomplished by locating the ends 30, 31 upon the central portion 32 and securing them thereon. The spring 51 and spring cups 50 are inserted in the plunger 41, and upon depressing these cups, the plunger is forced into the opening of the shaft end 31, and pushed along until the spring cups 50 are forced outward by the spring 51 into the slots 39.

When the door has been properly bored with the holes E, F and the mortise 12 formed therein, the latch bolt assembly is forced into the cylindrical hole E, and is secured thereby by the wood screws 70 passing through suitable apertures in the end flange 11, and it will be remarked that by having the end flange 11 of semicircular end formation, these screws will enter the holes formed by the augur bit in producing the mortise 12. It will be understood that the center of the hole F is located a predetermined distance from the edge of the door corresponding to the size of the latch members, and from Fig. 1 it will be seen that this hole F is somewhat larger than the external diameter of the knob shaft including the cam 60. With the latch bolt assembly in position, the beveled end 13 of the latch bolt is pushed inward to the retracted position, and the end 30 of the knob shaft is passed through the opening existing between the latch bolt slider 15, the bridge 17 and the securing pin 65. It will be noted that the cam 60 is of substantially the same thickness as the bridge 17, and this in turn of the same thickness as the width of the slots 19 (Fig. 8), and that the chord defining the cut away portion opposite the cam 60 (Figs. 2 and 14) is not longer than the external diameter of the knob shaft members 30, 31, 32, so that the knob shaft can slide freely into the aforesaid space adjacent the bridge 17 when it is in the position shown in Fig. 2, and the latch bolt has been fully retracted, and the knob shaft is occupying a position slightly nearer the edge of the door than that which it will occupy when secured in its final location. As soon as the knob shaft is in its proper position, the beveled end 13 is re-

leased so that the bridge 17 enters the cut away portion 62. The flanged knob shaft journal members 71 are then slipped over the ends 30 and 31 of the knob shaft, after suitable depressing of the spring cups 50 in the case of the latter end 31, and brought up flush against the faces of the door D; the axis of the knob shaft is now displaced a short distance away from the edge of the door and the journal members or face plates 71 are secured in such position by screws 72 so that a firm support is afforded for the knob shaft. The respective knobs may now be slid over the ends of the knob shaft and secured there-to by the screws 38.

The latch may be disassembled and removed from the door in an inverse manner, as for example by removing the knob K and the screws 72. The beveled end 13 of the latch bolt is then pushed to its extreme position, while the knob shaft is moved closer toward the edge of the door, and then pulled toward the right in Fig. 1 so that it may be totally withdrawn. The screws 70 may then be removed and a tool introduced through the hole F to force the latch bolt and its sleeve assembly out of the hole E.

The operation of the device when assembled in the door is as follows: With the parts in the positions of Figs. 1 and 2, if either knob is rotated, the central member 32 of the rigid knob shaft is likewise rotated so that a corner of the cam portion 60 is forced with a sliding movement against the face of the bridge 17, to produce a movement of the bridge toward the right in Fig. 2, against the action of the return spring 22 until the position of Fig. 14 is reached. At this position, by reason of the relative location of the axis of the knob shaft with respect to the edge of the door, the slider members 15 of the latch bolt have been retracted or moved toward the right in Fig. 2 until the outer end of the slot 18 has been brought into contact with the projecting lugs 20 of the spring stop plate, this stop plate 21 having been held in position by the locking pin 65 secured in the latch tube 10. This forms a stop or arresting point for the retractive movement of the latch bolt, so that the knob shaft cannot be turned through 360°. During the rocking of the knob shaft and the movement therewith of the bridge 17 and the other elements of the latch bolt proper, the projecting external portion of the cam 60 passes into one of the slots 19, and hence the knob shaft is prevented from axial movement while in such rotated position, just the same as it has theretofore been prevented from axial movement by the engagement of the bridge 17 in the cut-away portion 62.

Upon releasing the knob, the spring 22 acts to project the latch bolt end 13 and by the slider members 15 operates to force the bridge 17 against the cam 60, thus causing a

return rotation of the knob shaft and knob to the position shown in Fig. 2.

It will particularly be noted that by turning the latch bolt tube 10 and associated parts 5 through 180°, the latch bolt is changed for operation with a door swinging from the opposition side of the door jam, without necessitating any change whatsoever in the method of drilling the holes or in the arrangement and location of the knob shaft and knobs. Likewise, the knob shaft and knobs are made substantially symmetrical so that the end 30 of the knob shaft may be introduced through the latch bolt assembly 10 from either side of the door, so that the blocking knob K_a may be located on either side of the door as preferred; and that if so desired the knob K_a may be reversed from one side of the door to the other by the single operation of releasing the screws 72 and 38, removing the knob 38 and one face plate 71 from the knob shaft, withdrawing the knob shaft from the door and then inserting it from the other side, replacing the face plate 71 and then the screws 72 and 38.

In order to block the latch so that the door is secured immovably from one side, the spring cups 50 are depressed between thumb and finger and forced relatively toward the door. As soon as the lugs 52 have cleared the corresponding notches 40, this movement is easily effected. Therewith, the plunger 41 is forced toward the left in Fig. 1, so that the tongue 43 engages relatively 30 behind the bridge 17, which as shown in Fig. 2 is then resting against the flat inner side of the cam member 60. In this way, the bridge 17 is held fixedly by engagement on both sides thereof whereby the latch bolt 35 and its beveled end 13 are prevented from movement so that the door cannot be released by the introduction of a prying tool against the beveled end 13. Further, the bridge 17 serves as a key between the cam 40 60 and the tongue 43 to prevent any rotation of the knob shaft, which latter being rigidly connected to the knobs K and K_a , results in the preventing of any movement of these knobs either from one side or the 45 other. The lugs 52 on the spring cups 50 engage in this blocking position of the plunger 41 in the notches 40a on the shaft end 31, so that no jarring or wrapping upon the door will cause an accidental or other undesired release of the blocking action.

When it is desired to release the latch, a person standing on the side of the door represented by the knob K_a , again depresses the spring cups 50 between thumb and finger 50 and slides them toward the knob K_a , therewith the tongue 43 of the plunger 41 is withdrawn from engagement with the bridge 17, so that now the latch can be operated freely, as before, from either side of the door.

It will particularly be noted that it is

necessary to operate both of the cups 50 in order to secure a movement of the plunger 41, thus affording a further assurance against accidental displacement, or operation by a young child.

It is obvious that the invention is not limited to the particular form of execution described and illustrated, but that it may be employed in many ways within the scope of the appended claims.

What I claim as new and desire to secure by Letters Patent is:

1. In a latch, a housing, a bolt slideable in said housing, interengaging means on the bolt and housing to prevent rotation of the bolt about its axis, a spring to project said bolt, and means rigid with the housing to cause a compression of said spring when the bolt is retracted, said means including a removable member secured in position in said housing by the pressure of said spring, said member upon removal permitting the withdrawal of the remainder of said means, said bolt and spring from said housing.

2. In a latch, a housing, a bolt slideable in said housing, and having intersecting longitudinal openings therein, a spring located in one of said openings and acting upon the bolt to project the same, means rigid with the housing and extending through another of said openings to cause a compression of said spring when the bolt is retracted, said means cooperating with the wall of said other opening to limit the movement of said bolt, and means engageable with said bolt to retract the same.

3. In a latch, an axially movable bolt, an operating shaft having a knob at its end, interengaging means on said bolt and shaft to prevent axial movement of the shaft and to cause axial movement of said bolt when the shaft is rotated, a plunger mounted in and movable axially along said shaft to cooperate with said interengaging means to prevent movement of said bolt and an operating device operatively engaged with said plunger and extending to the exterior of said shaft between said bolt and knob for moving said plunger.

4. In a latch, a slide bolt, a hollow shaft having a longitudinal slot therein, said shaft being cut away to receive the bolt in its projected position and to provide a bolt actuating cam for moving the bolt to the retracted position, said bolt having a bridge to enter said cut away portion and to cooperate with said cam, a plunger having a tongue and slidably located in said hollow shaft, and having a transverse hole opposite said slot, said plunger being movable in the direction of said shaft to press said tongue in engagement with the side of said bridge opposite said cam whereby to retain the bolt against retraction, a spring cup movable in said hole and slot and adapted to be moved inward by direct

- manual engagement, a spring to force said cup outward, and means to limit the inward movement of said cup and to retain the cup in a predetermined position in said slot, said cup while in an inwardly moved position being free of said retaining means so that the plunger may be moved axially in said shaft by a manual axial movement of the inwardly pressed cup.
5. A latch as in claim 4, in which a bearing member is provided for the shaft and to be secured to the door, said cam extending beyond the shaft periphery thereby preventing the movement of said member from end to end of said shaft, said spring cap being compressible beneath the peripheral surface of said hollow shaft whereby to permit the movement of said bearing member over the same, said cup in its outer position projecting beyond the surface of the shaft and preventing movement of the bearing member along the shaft past said cup.

In testimony whereof, I affix my signature.
JOSEPH LOUIS SCRIVENER.
